CLAIM

The ornamental design for a stackable bar stool having a back, as shown and described.

DESCRIPTION

FIG. 1 is a front view of our stackable bar stool having a back; FIG. 2 is a left side view thereof, the right side view being a mirror image thereof;

FIG. 3 is a rear view thereof;

FIG. 4 is a top view thereof;

FIG. 5 is a bottom view thereof;

FIG. 6 is a front perspective view thereof; and,

FIG. 7 is a rear perspective view thereof.
